(57) **CLAIM**

We claim the ornamental design for a food slicer, as shown and described.

DESCRIPTION

FIG. 1 is a bottom perspective view of a food slicer of the present invention;

FIG. 2 is a first side view thereof, wherein the second side view is a mirror image thereof;

FIG. 3 is a bottom view thereof;

FIG. 4 is a top view thereof;

FIG. 5 is a front view thereof; and,

FIG. 6 is a rear view thereof.

The ornamental design which is claimed is shown in solid lines in the drawings. Any broken lines in the drawings are for illustrative purposes only and form no part of the claimed design.
